(57) **CLAIM**

The ornamental design for a bluetooth speaker, as shown and described.

DESCRIPTION

FIG. 1 is a front elevational view of a bluetooth speaker showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown form no part of the claimed design.

1 Claim, 6 Drawing Sheets

FIG. 1

FIG. 2

FIG. 3

FIG. 4

FIG. 5

FIG. 6

FIG. 7
